MULTIPLE BROOCH CONSTRUCTION

Oscar Frank Placco, Providence, R. I., assignor
to Cohn & Rosenberger, Inc., New York, N. Y.,
a corporation of New York

Application November 9, 1935, Serial No. 49,058

4 Claims. (Cl. 63—20)

My present invention relates to the jewelry art, and has particular reference to a novel construction suitable for brooches, clips, and the like.

5 The present invention relates to jewelry ornaments of the multiple type, comprising a base which has means for detachably securing to a garment or the like, and one or more ornaments which may be detachably secured to the base, 10 and which have clamps, pins or other securing means, whereby the ornaments may be removed from the base and independently used.

It is the principal object of my invention to devise an ornament construction which may be 15 used as an ornament per se, and which has combined therewith one or more additional ornaments that may be detachably secured thereto, such ornaments having independent garment engaging means, and having designs which cooperate with and supplement the ornament design 20 of the base so as to create a plurality of different jewelry ornaments when used independently of or together with the base.

With the above and other objects and advantageous features in view, the invention consists 25 of a novel arrangement of parts more fully described in the detailed description following, in conjunction with the accompanying drawing, and more specifically defined in the claims appended thereto.

In the drawing,

Fig. 1 is a plan view of a novel ornament base, which is ornamental per se;

35 Figs. 2, 3, and 4 are respectively front, back and side views of novel ornaments removably securable to the ornament base shown in Fig. 1;

Fig. 5 is a view, partly broken away, showing the novel separable ornaments secured to the ornament base;

40 Fig. 6 is an enlarged section on the line 6—6 of Fig. 5;

Fig. 7 is a side view of Fig. 5;

Fig. 8 is a front view of a modified ornament base;

45 Figs. 9 and 10 are respectively front and rear views of supplemental ornaments therefor; and

Fig. 11 is a view showing the supplemental ornaments mounted on the modified base.

It has been found desirable to provide a multiple ornament construction for use as a jewelry ornament, comprising an ornamental base which may be used by itself, and having one or more supplemental ornaments which may be detachably secured to the base to form a composite 55 ornament, the supplemental ornaments being

provided with individual securing means so that they may be independently used. The supplemental ornaments may be used so as to supplement the design of the ornamental base or may be used so as to cover the design of the ornamental base and thus create an entirely new design.

The novel ornament construction preferably consists of an ornamental base 10, see Fig. 1, which has garment securing means attached thereto, as indicated in Fig. 7, one type of garment securing means consisting of a pin 11 hinged at one end in pivot ears 12, and having a lock catch or similar device 13 at the other end for releasably receiving the pin end. The ornamental base 10 preferably has ornamental 15 configurations 14 thereon, whereby the base may be used as an ornament. One or more openings 15 are also provided, for receiving clamps 16 of supplemental ornaments 17 whereby the opened clamps may be passed through openings 15 and then moved to closed position, as indicated in Fig. 4, for retention in such position by coil springs 18; the clamps are hingedly mounted in standards 19 on the back of the supplemental ornaments, whereby one or both of the supplemental ornaments 17, when detachably mounted on the ornamental base 10, combine with the ornamental configurations 14 or parts thereof to form an entirely new ornamental design. The supplemental ornaments 17 may be detached from the ornament base 10 to form independent ornaments, such as for example shoulder clips or the like, the clamps having teeth 20 for detachably engaging the garment parts when so used.

30 The above described construction utilizes an ornamental base and one or more supplemental ornaments which combine with the ornamental base so as to form a new ornamental design utilizing part or all of the ornament configurations of the base; it is preferred for certain constructions to provide supplemental ornaments which at least completely cover the central portion of the ornamental base, thus forming an entirely new design which has the advantage of 35 being in raised relation to the ornamental base so as to create a richer and more attractive appearance.

To this end I provide an ornamental base 20, see Fig. 8, which is ornamental per se, and which has openings 21 for receiving the clamp elements 22 of supplemental ornaments 23, these supplemental ornaments and their clamp elements being similar in structure and function to the supplemental ornaments 17, whereby they have inde-

pendent use as ornamental clips or the like, and being detachably securable to the ornamental base 20 by extending the clamps 22 through the openings 21, and then retaining them in closed position under the influence of their springs 24, whereby the composite ornament presents the appearance shown in Fig. 11, the two ornaments 23 being mounted on top of the central ornamentation of the base ornament so as to present 10 an entirely different ornament of substantial thickness, whereby the richness of the ornamental effect is enhanced, and particularly when the ornaments include stones, as for example rhinestones and the like.

15 It is thus evident that the novel ornamental combination includes a plurality of separable members each individually usable, which combine together to produce novel ornamental effects of great richness, as the thickness of the composite ornament enhances the attractive appearance thereof.

20 While I have described specific constructional embodiments of my invention, it is obvious that changes in the shape, form, and materials used 25 for the various parts, in the type of individual securing means or attaching means used, and in the relative arrangement and mounting of the various parts, may be made to suit the requirements for different ornamental effects, without 30 departing from the spirit and the scope of the invention as defined in the appended claims.

I claim:

1. In combination, a base having an ornamental surface with a border, an opening in said 35 base having a seat therearound, and a supplemental ornament having a clamp hinged thereto, said ornament being larger than said opening and adapted to contact the seat on the ornamental surface of said base and said clamp being 40 adapted to extend through said opening when in open position and having spring means for locking said clamp against the under surface of said base to detachably secure said supplemental orna-

ment in superimposed relation to the base ornamental surface and within said border.

2. In combination, a base having an ornamental surface with a border, spaced openings in said base each having a seat therearound, and supplemental ornaments each having clamps hinged thereto, said ornaments being larger than said openings and adapted to contact the seats on the ornamental surface of said base and said clamps being adapted to extend through said 10 openings when in open position, and having spring means for locking said clamps against the under surface of said base to detachably secure said supplemental ornaments in superimposed 15 relation to the base ornamental surface and within said border.

3. In combination, a base having an ornamental surface, spaced openings at each end of said base each having a seat therearound, and supplemental ornaments each having clamps hinged thereto, said ornaments being larger than 20 said openings and adapted to contact the seats on the ornamental surface of said base and said clamps being adapted to extend through said 25 openings when in open position, and having spring means for locking said clamps against the under surface of said base to detachably secure said supplemental ornaments in superimposed relation to the base ornamental surface.

4. In combination, a base having an ornamental surface, spaced openings at opposite corners of said base each having a seat therearound, and supplemental ornaments each having clamps hinged thereto, said ornaments being larger than 30 said openings and adapted to contact the seats on the ornamental surface of said base and said clamps being adapted to extend through said 35 openings when in open position, and having spring means for locking said clamps against the under surface of said base to detachably secure 40 said supplemental ornaments in superimposed relation to the base ornamental surface.

OSCAR FRANK PLACCO.
